(57) **CLAIM**

The ornamental design for a clamp, as shown and described.

DESCRIPTION

FIG. 1 is a perspective view of the clamp for holding documents, drawings, plans and the like within a storage/filing system, the clamp jaws being shown in a closed position;

FIG. 2 is a view from one end with part of an end cap cut away to better illustrate the profile of the jaws as seen at that end;

FIG. 3 is an opposite end view;

FIG. 4 is an end view showing the jaws in an open position;

FIG. 5 is a top plan view;

FIG. 6 is a front elevational view;

FIG. 7 is a rear elevational view; and,

FIG. 8 is a bottom plan view.

The broken lines in the figures are for illustrative purposes only and form no part of the claimed design.
